UNITED STATES PATENT OFFICE

DAVID WEISBERGER, OF NEWARK, NEW JERSEY

DISPLAY DEVICE FOR AUTOMOBILES

Application filed July 20, 1927. Serial No. 207,023.

This invention relates to display devices intended particularly for use in closed-body motor vehicles. The device may in addition support various articles of comfort or convenience, including receptacles for cigarettes, matches, ashes and containers for toilet materials and, in fact, any desirable facilities which may be placed conveniently in the vehicle.

10 It has been usual heretofore to provide brackets with screws for attaching devices such as those mentioned to the walls of motor vehicles. Attachment in this manner requires the drilling of holes and unless carefully done the drilling may mar the fine finish of the surface to which the device is attached. Furthermore, when so attached the device becomes a permanent fixture and it cannot be removed without leaving a disfiguring mark. If the device is damaged and another exactly like it cannot be found, the unsightly drilling may be exposed when a new device with a different bracket is substituted.

25 It is the object of the present invention to provide a simple and inexpensive support for various articles of convenience or utility which may be mounted thereby in closed motor vehicles without necessitating the drilling or cutting of the interior walls or upholst-

30 ery.

A further object of the invention is the provision of a support for various articles which is adjustable and adapted to be secured 35 rigidly in the desired position so as to avoid rattling.

The invention is designed more particularly as a display device although as indicated it is useful for other purposes. It is 40 desirable to display in motor vehicles certain cards and the like which may, for example, identify the owner of the vehicle as a member of automobile associations, insurance organizations and the like. Such cards should 45 be supported so that they are protected from dust and are visible from the exterior of the vehicle. The support should otherwise be relatively inconspicuous so as to avoid disfiguring the vehicle. No acceptable display de-

vice fulfilling all of these requirements has been available heretofore.

In carrying out the invention I provide a bracket which is adapted to be secured to the window-frame of the vehicle without drilling or inserting screws in the frame. The bracket may support a frame in which a card or cards may be mounted so as to be visible through the window. The device is designed to avoid rattling and interference with the raising and lowering of the window. The card or cards are protected preferably by a suitable transparent covering so that they will not be disfigured by moisture and dust even when the window of the vehicle is open.

55 The bracket may serve also to support various conveniences as hereinbefore indicated.

The device may be made conveniently of sheet metal with two legs which are connected at the top either by an integral resilient bridge or by means of a hinge or hinges so as to permit relative movement of the legs toward and from each other. At their lower edges the legs may be shaped to engage the window-sill of the vehicle. One 60 leg which is disposed adjacent to the glass may be straight except for a lip turned inwardly at the lower edge to firmly grip the window-sill. The inner edge of the sill varies 65 in form in different vehicles. It may be straight or rounded and the corresponding leg of the bracket may be similarly shaped. It should be formed preferably with a lip 70 turned inwardly at its lower edge.

75 To firmly clamp the bracket to the sill the bracket is provided intermediate the lower edges and the connecting bridge with a lock 80 preferably in the form of threaded members adapted to cooperate. The face of one leg 85 may be embossed to provide a seat with an opening therein through which one threaded member is inserted. The head of the threaded member is seated in the boss so that it is 90 below the normal surface of the leg. The other leg is provided with a slot through 95 which the other threaded member is inserted. When the threaded members are connected the device can be firmly clamped in position.

To avoid theft of the device the second 100 threaded member may likewise be seated in

a boss and it may have a small squared head so that it cannot be turned easily with a wrench or similar tool. A key which can be inserted in the boss to permit operation of the threaded member may be provided to facilitate securing the bracket to the vehicle.

The card or cards can be secured to the bracket in various ways. The leg which is contiguous to the window can be provided with simple clips in which the card may be inserted. Preferably, however, a frame is provided. This may be of metal or other material and it may be adapted to hold one or two cards. The frame may be held in clips provided on the leg of the bracket so that it can be removed and turned to display either of the cards. Or the frame may be hingedly or otherwise connected to the leg. The frame may have one or two transparent faces to protect the cards therein or a pocket with a transparent face may be provided on the leg of the bracket to receive the frame carrying the cards. Various other modifications of the card support will suggest themselves.

The opposite leg of the bracket may support a receptacle or other convenience. The latter may be permanently secured to the leg or it may be held by suitable clips so that it is readily removable.

Although the device is capable of numerous variations it will be described more particularly with reference to the accompanying drawing illustrating the preferred embodiments; in which

Fig. 1 is a view in perspective of the display device;

Fig. 2 is a transverse sectional view thereof;

Fig. 3 is a transverse sectional view of a slightly different form of the invention;

Fig. 4 is an elevation of the device;

Fig. 5 is a transverse sectional view of another form of the invention;

Fig. 6 is a view in perspective of the device as illustrated in Fig. 5; and

Fig. 7 is a view in perspective of the card holder.

Referring to the drawing, the bracket comprises legs 5 and 6 which are connected by a resilient bridge 7 which permits relative movement of the legs. The leg 5 is provided at its lower edge with a lip 8 turned inwardly to slip under the lower edge of the window-sill 9. The leg 5 is disposed between the sill 9 and the window-glass 10. The other leg 6 may be rounded at 11 to fit the inner edge of the sill with a lip 12 which engages the sill to hold the bracket in the desired position when it is clamped.

The leg 5 is embossed at 13 and has an opening 14 through which a threaded member 15 is inserted. The head 16 of the threaded member 15 is seated in the boss. The leg 6 has a slot 17 to receive the threaded member 18. The latter is provided with a knurled

head 19 to facilitate manipulation. The slot 17 permits the alignment and engagement of the threaded members. When the threaded members are engaged the legs 5 and 6 may be drawn together and firmly clamped in the desired position on the window-sill. The ends of the clamp are closed by wings 19' which overlap.

The leg 5 may have a plurality of clips 20 in which the card or other display 21 is held. This leg is adjacent the window-glass 10 so that the card is visible through the windows. The card can be protected by a transparent covering if desired.

In Fig. 3 of the drawing the legs 22 and 23 are hingedly connected at 24 so as to permit relative movement. The device and the parts thereof are substantially as hereinbefore described.

In Figs. 5 and 6 I have illustrated a modified form of the device in which the legs 25 and 26 are hingedly connected at 27. The leg 25 is provided with a lip 28 to engage beneath the window-sill and the leg 26 is shaped to engage the other side of the sill. A boss 29 is formed in the leg 25 with an opening 30 to receive the threaded member 31, the head 32 of which rests in the boss. The leg 26 is likewise provided with a boss 33 and a slot 34 through which a threaded member 35 is inserted to cooperate with the threaded member 31. The threaded member 35 has a collar 36 and a small squared head 37 which does not project beyond the normal surface of the leg. The threaded member can be turned by means of a suitable key (not shown) which is adapted to engage the squared head 37. The ends of the device are closed by wings 37'.

A pocket 38 with a transparent front 38' is secured to the leg 25 and is adapted to receive a frame 39 in which cards 40 and 41 are mounted. The frame 39 may be inserted and removed as may be necessary to display either card.

A cover 45 is hingedly connected to the leg 26 and is held by a clip 46. The cover supports a receptacle 47, for example, an ash tray or other receiver which is thus accessible to the occupants of the vehicle.

The invention as described affords a simple and satisfactory display device to support cards and the like. It can be easily secured to the vehicle without marring the surface and is easily removed. The card or cards displayed therein can be observed through the window of the vehicle and they are protected from moisture and dust.

Various changes can be made in the details of construction and arrangement of the parts without departing from the invention or sacrificing any of its advantages.

I claim:-

1. In a device to be attached to closed-body motor vehicles having a window and frame

therefor, a bracket comprising spaced connected legs adapted to grip the window-frame and clamping means intermediate the upper and lower edges of the legs whereby the device is securely held in adjusted position,
5 including threaded members supported in the legs, the ends of the threaded members being countersunk below the normal surface of the legs and means on one of the legs to support
10 a display card, the display card supporting means covering the countersunk ends of one of the threaded members.

2. In a device to be attached to closed body motor vehicles having a window and a frame therefor, a bracket comprising spaced legs connected at one end and having extensions within turned lips at their opposite ends adapted to grip the window frame, overlapping wings at the lateral ends of the legs, clamping means intermediate the upper and lower edges of the legs whereby the device is securely held in adjusted position, and means on one of the legs to support a display card.

25 3. In a device to be attached to closed body motor vehicles having a window and a frame therefor, a bracket comprising spaced legs hingedly connected at one end and having extensions with inturned lips at their opposite ends adapted to grip the window frame, overlapping wings at the lateral ends of the legs, clamping means intermediate the upper and lower edges of the legs whereby the device is securely held in adjusted position, and means
30 on one of the legs to support a display card.

In testimony whereof I affix my signature.
DAVID WEISBERGER.
